The ornamental design for a toy vehicle, as shown and described.

DESCRIPTION

FIG. 1 is a top, right side perspective view of a toy vehicle showing our new design;

FIG. 2 is a bottom, right side perspective view thereof;

FIG. 3 is a right side view thereof;

FIG. 4 is a left side view thereof;

FIG. 5 is a rear view thereof;

FIG. 6 is a front view thereof;

FIG. 7 is a top view thereof; and,

FIG. 8 is a bottom view thereof.

The features shown in broken lines are portions of the toy vehicle forming no part of the claimed design. The features shown in long dash-short dash bolded broken lines indicate the bounds of the claimed design and otherwise form no part of the claimed design.
